PACKING CASE OR CRATE.

Application filed January 6, 1926. Serial No. 79,635.

This invention relates to improvements in packing cases or crates for use in shipping canned goods, particularly cans containing relatively heavy liquids or fluids.

5 A principal object of the invention is to provide a packing case or crate for holding a plurality of cans packed compactly, but separated from rubbing contact to prevent chafing and marring of the labels on their

10 sides. Another important object of the improvement is to provide separating and steadyng means for the cans which act as struts to brace the top and bottom of the cases against the strain and load imposed in handling and stacking one case on another, so as to protect the cans from rupture and damage.

Another object of the invention is to provide a packing case or crate of the type 20 specified which, while being stronger and more efficient for the purpose explained, is relatively simple in structure and economical to manufacture.

Further objects of the improvement are set 25 forth in the following specification which describes a preferred embodiment of the invention as illustrated by the accompanying drawings. In the drawings:

Fig. 1 is a plan view of the improved 30 packing case or crate, showing it with the cover removed to illustrate the arrangement of the cans contained therein;

Fig. 2 is a sectional elevation of the same taken on line 2—2 of Fig. 1; and

35 Fig. 3 is a similar sectional view taken on line 3—3 of Fig. 1.

My improved packing case or crate is designed particularly for shipping tin cans or similar containers filled with relatively 40 heavy fluids such as paint in dry, liquid or paste form, but it is also adapted for use with other type of containers for different kinds of commodities. Paint sold through the retail trade is usually packaged in 45 cylindrical cans bearing suitable labels pasted or lithographed on their sides and the larger cans containing quarts, half-gallons or more are relatively heavy so that they require careful packing to prevent damage 50 under handling or in transit. If the cans are left relatively loose in the case they will strike against each other and become dented and their seams may be bulged and ruptured to cause leakage of the contents. Moreover,

the rubbing and chafing between the sides 55 of the cans will tear or mar the labels thereon, rendering them unsightly and the merchandise therein unsalable. For this reason it has sometimes been the practice to separate the cans in the case by cross partitions similar to those in an egg-crate. Such a separating means has not been found entirely satisfactory, however, as the cans will still be subject to a sliding and turning movement which, if the partitions are not 60 of the proper depth, causes the cans to be rubbed and chafed and the labels thereon torn or marred. Moreover, the cross partitions increase the bulk and add to the cost 65 of the case while also increasing the weight 70 and thereby the cost of transportation.

Various other expedients have been tried for holding the cans in place in the case to prevent chafing therebetween and rupture 75 of their seams, but heretofore none has been entirely satisfactory for the purpose intended. My present invention overcomes the above mentioned defects and deficiencies in 80 previously used cases through an arrangement of separators taking the form of struts extending from top to bottom of the case between the cans packed therein.

Referring to the drawings, I may employ the usual type of wooden box or case 2 composed of boards dovetailed, nailed or otherwise fastened together. The case 2 may be of any suitable size and shape to accommodate the desired number of cans, and as herein illustrated by way of example only, the case is designed to hold six cans 3 standing on 85 their bottoms. The interior depth of the case is substantially equal to the height of the cans, but to allow for the shrinkage of the wood and inaccuracies in manufacture a clearance must be provided between the top 90 of the cans and the under side of the cover 4, see Figs. 2 and 3.

The interior length and width of the case 2 are proportioned to permit the cans 3 to be placed therein side by side in rows in 100 adjacent relation, but with a clearance between their sides. It will be noted by reference to Figs. 2 and 3 that the cans 3 have projecting beads 5 at top and bottom, where their ends are flanged outwardly to join 105 them to the cylindrical sides. When the cans 3 are placed in the case 2 in the manner as above explained there will be a slight

clearance between the edges of the flanges or beads 5, and my improved holding means or separating elements 6 are adapted to engage with the rims of the flanges 5 to prevent contact between the rims and bodies of the cans 3 when they ride up in the case.

For this purpose the separators 6 are constructed in the form of spool-shaped struts or braces comprising longitudinal strips of wood 7 extending between enlarged blocks or heads 8. For the sake of economy in cost of manufacture the body strip 7 may be an ordinary wooden stick of square or rectangular cross-section and the heads 8 are also square as sawed from a wider strip; although if desired the shank or body 7 may be cylindrical and the heads 8 circular. The heads 8 may be fastened to the ends of the stick 7 in any suitable manner, for instance, by means of nails 9 as illustrated in Fig. 3. As a further modification in the structure of the separator the heads 8 might be held apart by a metal rod instead of the wooden stick 7. The length of the separator or strut 6 is made to coincide accurately with the interior depth of the box or case 2, this being important in order that when the cover 4 is fastened in place it will rest against the top of the upper heads 8 to be supported and braced from the struts which function in the manner and for the purpose as hereinafter more fully explained.

When bails are applied to the cans or containers 3 to adapt them for use as pails, projecting ears 10 are provided on their sides for receiving the hooked ends of the wire handles. Preferably, the handles or bails are removed from the cans and shipped loose in the case, although they may remain in place on the cans without danger of their rubbing on adjacent cans since the sides of all the cans are held in spaced relation in the cases. The cans 3 are preferably placed in the case with the ears 10 arranged to abut one of the sides thereof as shown in Fig. 1, as they will thus have a tendency to hold the cans from turning to any considerable extent on their bottoms, thereby preventing the ears on one can from rubbing or chafing against the sides of an adjacent can.

As the cans 3 are placed in the case 2 the struts or separators 6 are inserted between the adjacent rows as illustrated in Fig. 1, with each separator acting as a spacing medium for a group of four adjacent cans. In the present illustration only two rows of three cans each are shown, but in other instances there may be a greater number of rows and more cans in each row, the cases usually containing six of twelve cans or multiples thereof. It is to be particularly noted that the heads 8 of the separators 6 are of an exact width or breadth between their sides to adapt them to fit snugly between the edges of the rims or beads 5 at the

top and bottom of the cans 3 to hold the latter against the sides of the case with little or no play therebetween. The depth of thickness of the heads or blocks 8 is of ample dimensions to prevent the bottom flanges or beads 5 on the cans 3 from riding up over the lower heads, and since the top of the upper heads abut the under side of the cover 4 of the case the top flanges 5 on the cans cannot ride thereover when the cans shift their position or slide longitudinally in the case. This feature is most important and results from the fact that the separators or struts 6 are continuous between the cover and bottom of the case.

Another advantage resulting from this arrangement, as before mentioned, is that the separators 6 act to brace the cover and bottom of the case to take the strain and load during handling or when the cases are stacked one on another. The top and bottom boards of the case are therefore prevented from springing or buckling to transmit the strain or load to the cans, and consequently the cans are protected against rupture at their seams which would result in leakage of the contents and spillage and spoilage of the goods. Heretofore this has been a very serious matter in packing and shipping canned goods. If the cans are allowed to chafe one on another as their end flanges ride up over the top of adjacent cans the labels are marred and their appearance spoiled while the cans themselves are apt to become dented and bruised. When a number of cases are piled or stacked one on another the considerable weight imposed on the bottom cases causes the covers to spring and sag and the load falls on the cans within the case. This frequently causes the sides of the cans to buckle or bulge and opens their seams so that the contents leak. The damaged cans are usually rejected by the consignee and this entails pecuniary loss to the consignor or manufacturer. With the present improved method of packing and staying or separating the cans in the case, while bracing the top and bottom thereof, the cans are held from rubbing contact on their sides; and still more important they are protected from strain or stress in handling and stacking the cases so that they can not be damaged or broken open to spill their contents.

While I have herein illustrated and described the invention in its simplest form, it is obvious that the size and shape of the improved case may be varied and the structure and arrangement of the separating means therein modified without departing from the spirit or scope of the invention as expressed in the following claims. I claim:

1. A packing case or crate for cans and other containers provided with spool-shaped struts having enlarged heads at their ends,

said struts extending between the cover and bottom of the case and abutting thereagainst to brace the case, and arranged between the cans with their heads bearing against the 5 rims thereof to hold the cans from rubbing contact on their sides.

2. As a new article of commerce, a packing case or crate for cans and other containers provided with wooden struts extending between the top and bottom of the case and abutting thereagainst to brace the case, said struts having enlarged heads fastened 10 to their ends to adapt them to bear against the top and bottom rims of the cans to hold

them from riding or rubbing on their sides. 15

3. A packing case or crate for cans and other containers comprising a bottom, sides and cover, and loose separators constructed with central struts and enlarged heads at their ends to adapt them to be placed in the 20 case between the top and bottom thereof to brace the same with their heads disposed between the cans and bearing against the sides thereof to prevent them from riding on or rubbing against each other. 25

In testimony whereof I affix my signature.

WAYLAND W. RICE.
